UNITED STATES PATENT OFFICE.

HENRY J. CASANOVA, OF CHICAGO, ILLINOIS.

FLYING-MACHINE.

980,489.

Specification of Letters Patent.

Patented Jan. 3, 1911.

Application filed October 9, 1909. Serial No. 521,812.

To all whom it may concern:

Be it known that I, HENRY J. CASANOVA, a citizen of the United States, residing at Chicago, in the county of Cook and State of Illinois, have invented certain new and useful Improvements in Flying-Machines, of which the following is a specification.

The invention relates in general to flying machines, but pertains more in particular to 10 a flying machine of a type embodying both the flying and gliding principle.

One of the principal objects of the invention is to construct a machine of the "heavier-than-air" type, capable of raising 15 itself from the ground by its own power.

Another object of the invention is to construct a machine in which means are provided for raising the machine from the ground and sustaining the same at any desired height, with further means for propelling the same forward.

To accomplish the foregoing objects, the machine consists broadly in a device having a stationary supporting plane with wings on 25 both sides thereof, capable of being moved vertically, and adapted to raise the machine from the ground and to maintain the same at the desired height, in combination with suitable propelling mechanism for driving 30 the machine forward in a line parallel with the longitudinal axis of the top plane.

One of the principal advantages of my invention resides in the construction of the aforesaid plane and wings, comprising certain 35 valve mechanism, reducing the superficial area of the plane and wings in an upward movement by the opening of the valves, and the valves closing in a downward movement.

40 A further advantage of my invention resides in the mechanism for propelling the machine, and particularly in a single shaft capable of operating propellers at both the forward and rear end of the machine, and to 45 which the wings are connected, whereby the weight of the machine is materially reduced by a simple and efficient construction.

Another advantage of the invention resides 50 in the material of which I construct the plane and wings of my machine, consisting of ordinary palm leaves, secured together, and strengthened by means hereinafter shown and described.

55 Another feature of the invention resides in the means for effecting the steering, which

consists in connecting one of the propellers to the driving shaft by means of a suitable coupling, whereby the propeller may be moved by the operator at different angles.

Still a further advantage of the invention is in the particular construction of the frame work, whereby the breaking of the frame will not disable the machine.

Further details and advantages of the invention, and particularly details of construction relating to the fans employed, composing the wings or planes, will be hereinafter more fully dwelt upon in the specification and are clearly shown in the drawings, in which—

Figure 1 is a top plan view of my machine. Fig. 2 is a longitudinal sectional view of Fig. 1. Fig. 3 is an end view of Fig. 1, the wings in Fig. 3 being at a different angle from that shown in Fig. 1. Fig. 4 is 70 a plan view of one of the sections composing the wings and top plane. Fig. 5 is a section on the line 5—5 of Fig. 4. Fig. 6 is a perspective view of part of the driving mechanism. Fig. 7 is a longitudinal sectional 75 view of Fig. 6. Fig. 8 is a detail partial sectional view of the frame construction.

Referring now more particularly to the drawings, 11 represents as a whole the platform of the machine, having suitable wheels 85 12 secured thereto. Secured to the platform are the upright standards 13, preferably composed of light material, such as wood or aluminum, and suitably braced, as shown at 14. Attached to the top of the uprights 90 13 is a suitable frame 15, composed of light material and considerably longer than the length of the frame 11, the latter frame 15 when covered, as hereinafter described, constitutes the stationary plane of the machine. 95

A sleeve 16 is secured, by means of the cross rods 17, to the upright standards 13, extending longitudinally relative to the body of the machine, and is adapted to have an oscillating or rotating movement for a purpose 100 hereinafter described. The shaft 18 extends through said sleeve 16 and in the preferred form has two propellers 19 and 20, at each end thereof; the propeller 19 adapted to drive the machine forward, and the propeller 20 adapted to have a pulling effect.

The propellers are preferably identical in their construction, but are reversed as to their blades in their position upon the propelling shaft, to push and pull, respectively. 110

Secured to the sleeve 16 are a series of cross rods 21, 21^a and 21^b, which normally lie in the same plane and in the preferred construction six of such cross rods are secured to the sleeve, each adjacent set forming the frame work for wings upon opposite sides of the stationary plane. The two end sets (21^a and 21^b) of the cross rods being suitably secured to the sleeve 16 by the joints 22, and the middle set of cross rods being loosely mounted on the sleeve 16 by means of the sleeves 23; the driving mechanism being so constructed and connected, as herein-after described, as to cause the two outside wings 24^a, 24^b and 25^a, 25^b on opposite sides of the plane to alternately move upward or downward and the middle wings 26^a and 26^b to be alternating in their movement on both sides relative to the movement of the outside wings.

In the preferred construction, the combined area of the two outside wings on either side of the stationary plane, viz: 24^a and 24^b, is equal to the area of the middle wing 26^a, so that the movement of the wings on both sides of the stationary plane result in the displacement of substantially the same volume of air, and therefore there is no tilting of the machine when the wings are moved.

From the foregoing description, it will be understood that when the wings 24^a and 24^b move downwardly, the wing 26^a will move upward, while the movement of the wings 25^a and 25^b is always in a reverse direction to the wings 24^a, 24^b and 26^a. The particular construction of the wings will be hereafter more fully described.

A sprocket wheel 27 is secured to the power shaft 18, the sleeve 16 being connected on either side of the sprocket wheel by means of the spanner 28. For effecting the driving of the power shaft suitable power means 29, such as a gasoline engine or any other suitable motive power, is secured to the frame 11, having a suitable sprocket 30 connected to the shaft 31, the sprockets 27 and 30 being connected by means of the chain 32 or other suitable belt means, whereby the operation of the engine 29 causes the rotation of the shaft 18 and correspondingly rotates the propellers 19 and 20.

For effecting the driving of the wings a suitable motive power, such as a gasoline engine 33, similar to the engine 29, is secured to the frame 11 and is provided with a suitable shaft 34, carrying the usual sprocket 35. Mounted upon the frame 11 are suitable standards 36, the ends of which afford bearings for the crank shaft 37, having the usual crank arms 38 and 38^a. The crank shaft is provided with a sprocket wheel 39 that is driven by the sprocket wheel 35 by means of the chain 40. A connecting rod 41 is connected with the crank arm 38 by

means of a suitable joint 42, at one end thereof, its other end being connected to a suitable brace 43 arranged between the cross rods 21 on one side of the shaft 18. The connecting rod 41 is connected to the brace 43 by means of a suitable pivot joint 44. A connecting rod 45 is secured to the crank arm 38^a by means of a suitable coupling 46 at one end, its other end being connected to an arm 47 secured at one end to the sleeve 16, the other end being provided with a suitable pivot joint 48 and secured to the other end of the connecting rod 45.

From the foregoing description, it will be noted that upon the rotation of the crank shaft 37 the connecting rods 41 and 45 move all of the wings herein shown, the connecting rod 41 rocking the cross rods 21 carrying the wings 26^a and 26^b, which are loosely mounted on the sleeve 16, while the connecting rod 45 has a pivotal connection with the arm 47, the latter being rigidly secured to the sleeve 16, will cause the rocking of the cross rods 21^a and 21^b, which are also rigidly secured to the sleeve 16, and as the connecting rods 41 and 45 are disposed upon opposite sides of the shaft 18, it will be seen that an upward movement of the connecting rod 41 produces a downward movement of the wing 26^b, and an upward movement of the wing 26^a, and a corresponding reverse movement of the connecting rod 41 produces a corresponding reverse movement of the wings. It will also be noted that an upward movement of the connecting rod 45 produces a downward movement of the wings 24^a and 24^b, and an upward movement of the wings 25^a and 25^b, and the corresponding reverse movement of the connecting rod 45 produces a reverse movement of the wings, as heretofore noted, so that there is an alternating movement between the middle wing on each side of the machine and the two smaller wings on each side.

In the construction herein shown, the crank shaft 37 is adapted to rotate to produce the movement of the wings, although it is obvious that by ordinary mechanical connections the shaft might be partially rotated so as to produce an oscillating movement resulting in the same operation of the wings, although not to so great an extent as when the shaft is entirely rotated.

The propellers 19 and 20 are of the ordinary construction, each being provided with four blades, and in the preferred construction two propellers are employed, one at the rear and one at the forward end, for driving and pulling, respectively, although it is obvious that the front propeller might be entirely omitted, if desired.

The steering of the machine is accomplished by moving the rear propeller at an angle to the axis of the shaft 18, whereby force will be exerted on the rear of the ma-

chine at different angles, according to the angle of the propeller, to effect the steering. For instance: If, as shown in Fig. 1, the driving propeller 19 were moved to the right, the machine's direction would be changed to the right, and a corresponding movement to the left would result in the turning of the machine to the left, whereas when the propeller shaft is in alinement with the shaft 18, the machine travels at an angle parallel to the axis of the driving shaft.

Secured to the rear end of the machine is a bracket 49, terminating at its lower end in a housing 50, within which is a universal joint coupling designated as a whole at 51, which coupling is connected at the rear end of the shaft 18 to the propeller shaft 52, carrying the propeller 19. The housing 50 is preferably made in two parts, secured together by the usual means, the rear end of the housing being provided with a slot 53, through which the propeller shaft 52 extends. A shoulder 54 is secured to the shaft 52 and to which the steering cables 55 are connected, said steering cables being led back to the body of the machine and secured at a suitable point adjacent the operator's seat 56.

It will be readily seen that by pulling upon one of the cables 55 the propeller shaft 52 may be moved within the slot 53, to turn the propeller at different angles. A suitable bracket 57 is secured to the forward end of the machine and its lower end terminates in a bearing for the propeller shaft 18. Side boards 58 are secured to either side of the body of the machine and are provided with suitable slots 59 permitting the free movement of the various braces operating the wings, which side boards prevent the air from passing through the body of the machine and thereby affecting in any way the operation of the wings.

As before stated, the top plane and the wings are preferably composed of a plurality of ordinary palm leaf fans 60, suitably secured together. To the marginal edge of each fan a strengthening member 61 is secured, which in the preferred form consists of a piece of aluminum wire stitched to the edge of each fan, as shown at 62, the ends of the wire being wrapped around the stem 63. Each fan is provided with one or more openings 64, the marginal edges of each opening having a frame work 65 suitably secured to the body of the fan and a valve 66 is hinged at one end to the body of the fan on its under side; suitable means being provided, such as a cord 67, for permitting the valve to only partially open.

It will be seen from the foregoing description that the valves being upon the under side of each fan, when the fan is moved upward the valve will open, allowing the air above to pass through the body of

the fan each valve will close and thereby the displacement of air will be greater in the downward movement of the fan than when the same is moved upward. To make each fan stronger, I preferably thread light wires 68 through the body of the fan and in the construction herein shown, three of such wires are threaded through the body so as to cross each other at right angles, at substantially the center of each valve opening, 75 and thereby not only make the body of each fan more secure, but further insure a stronger structure to support the valve mechanism. In the preferred construction, each fan is secured to a brace 69 by nailing or otherwise 80 securing the stem 63 to said brace and as the fans are interposed one upon another to form a laminated structure with the stems of each fan in substantial alinement with the brace to which they are secured, an ex- 85 ceedingly homogeneous and durable structure is thereby provided.

While I have particularly described and shown palm leaf fans as composing the body of the wings and the top plane, I nevertheless do not limit myself to this particular article, as it is obvious that the wings might be composed of other material, having the described valve mechanism connected therewith, and it is further obvious that metal 95 pieces stamped from aluminum or other like material might be made in the form of fans and secured together in the manner as heretofore described.

I have selected palm leaf fans for the 100 reason that they are extremely durable, exceedingly light and are so naturally constructed with crevices and pockets that the air does not slide freely therefrom and they thereby are better adapted for the purposes 105 intended than an ordinary smooth or flat piece of material would be.

The top plane is provided with valves for the reason that the air pressure against the same will not be so great when the machine 110 rises and as the machine moves forward in its gliding movement the valves will be closed and a greater supporting surface be thereby obtained.

In my preferred form of construction, I 115 preferably make the entire frame work of hollow pieces of material, such as bamboo, aluminum piping or other like material, and to prevent the disabling of the machine in case any parts of the frame should break, 120 I secure a cable 70, which is preferably composed of wire, within the hollow frame work 71, the ends of said cable being suitably secured at various points, so that if the frame 71 breaks the parts thereof will 125 be held in substantial alinement, so as to prevent the entire collapsing or the disabling of the machine to such an extent that control over the same would be lost. I also preferably employ such cables within the 130

hollow frame work constituting the body, the upright frame and the frames for both the top plane and the wings. If further strength in the structure is desired, particularly in the wing construction, I reinforce the same by means of the truss wires 72.

As before stated, the principle of operation of the machine is not based solely on the gliding principle nor on the theory that the machine can be raised entirely by means of its wings, but rather upon a combination of the two principles.

The mode of operation is as follows: The wings are first operated rapidly and the propellers set in motion so as to have two forces exerted, one to lift the machine and the other to drive the same forward; the two forces combined with the top plane will result in the machine having both an upward movement and a forward movement until the desired elevation is reached, whereupon the wings may be all brought into a position parallel with the top plane and the machine moves forward on the gliding principle or the wings may be kept moving sufficiently to help sustain the machine at its desired height, and in actual practice I prefer to keep the wings constantly in motion varying the rapidity with which the wings move according to the varying air currents and the wind velocity. By keeping the wings constantly in motion, the lateral stability of the machine is assured and the longitudinal stability may be regulated by movement of the operator or other well known ways, such as by shifting weights.

It is obvious from the foregoing description that I have not limited myself to the particular construction and arrangement of parts herein shown and described, and therefore, without limiting myself to the many details and modifications, I claim.

1. In a flying machine, the combination of a suitable body, a stationary plane secured thereto, wings disposed on opposite sides of said plane, a shaft disposed beneath said stationary plane and arranged parallel to the longitudinal axis thereof, propellers on said shaft at each end thereof, sleeves on said shaft to which the frame work of said wings is secured, and means for rotating said shaft to drive the propellers and for oscillating said sleeve to operate said wings.

2. In a flying machine, the combination of a body, a plane secured thereto, a shaft, a propeller on said shaft, means for driving said shaft, wings disposed upon opposite sides of said plane and mounted on said shaft, said wings having valve mechanism therein adapted to open on an upward movement thereof and to close on a downward movement, and means for alternating the stroke of said wings on opposite sides of said plane.

3. In a flying machine, the combination of

a suitable body, a stationary plane secured thereto, a propeller shaft disposed beneath said plane and extending beyond the ends thereof, propellers secured to the ends of said shaft, means for driving said shaft, a sleeve on said shaft, frame work adapted to carry wings secured to said sleeve, wings secured to said frame work having valve mechanism therein adapted to open in an upward movement of said wings and to close on a downward movement thereof, means for oscillating said sleeve to produce movement of said wings in a vertical plane, and means for steering said machine.

4. In a flying machine, the combination of a body having wheels secured thereto, frame work secured to said body and having a plane at the top thereof of greater length than said body, side plates secured to said frame, a propeller shaft secured to said frame, disposed beneath said plane and lying parallel to the longitudinal axis of said plane, propellers at the ends of said shaft, means for moving one of said propellers at an angle to said shaft, a sleeve on said shaft, one or more frames secured to said sleeve and loosely mounted thereon, said frames adapted to carry wings, one or more frames rigidly secured to said sleeve and adapted to carry other wings, the area of said last-mentioned wings on one side of said machine being equal to the total area of the wings on the opposite side of said machine, valve mechanisms in said wings adapted to open in a vertical movement thereof and to close in a downward movement and means for oscillating said sleeve whereby the frames rigidly secured thereto will have an alternating vertical movement relative to the frames loosely mounted on said sleeve.

5. A flying machine, comprising a body member, a plane, a series of wings and propellers, a shaft disposed beneath said plane and to which said propellers are secured, a sleeve on said shaft upon which said wings are rigidly and loosely mounted, means for rotating said shaft and for oscillating said sleeve whereby the wings rigidly secured thereto have an alternating movement upon opposite sides thereof, and means for giving the wings loosely mounted on said sleeve a reverse alternating movement to that of the wings rigidly mounted thereon.

6. A flying machine, comprising in combination a body member, a stationary plane secured thereto and located above the same, a shaft disposed beneath said plane, propellers mounted at the ends of said shaft, a sleeve on said shaft, a series of frames secured to said sleeve adapted to carry wings, wings secured to said frames comprising a series of palm leaf-shaped members suitably secured together, each leaf member having one or more valves therein adapted to open in an upward movement of said wings and

20

25

to close in a downward movement, and means for rotating said propellers and for moving said wings vertically.

7. In a flying machine, a wing consisting of a plurality of sections of like material, the edges of each section reinforced, said sections being secured together, each section provided with a valve and a series of strengthening members passing through said sections to hold the same together and to reinforce the valve.

8. In a flying machine, a wing or plane composed of a series of natural dried and cured leaves suitably secured together, the marginal edges of each leaf reinforced, one or more openings in each leaf and a valve

secured adjacent each opening and adapted to close said opening on an upward movement of said wing or plane and to close on a downward movement thereof.

9. In a flying machine, a wing or plane composed of a series of palm leaves suitably secured together, the marginal edge of each leaf reinforced, one or more openings in each leaf and a valve secured adjacent to each opening and adapted to open on an upward movement of said wing or plane and to close on a downward movement thereof.
